ROBERT PFEIL, OF GRUNEWALD, NEAR BERLIN, GERMANY, ASSIGNOR TO SIEMENS & HALSKE, A. G., OF BERLIN, GERMANY, A CORPORATION OF GERMANY.

MERCURY SWITCH FOR RAILWAYS AND THE LIKE.

No. 889,963.

Specification of Letters Patent.

Patented June 9, 1908.

Application filed January 6, 1908. Serial No. 409,585.

To all whom it may concern:

Be it known that I, ROBERT PFEIL, a subject of the German Emperor, and residing at Beymestrasse 28-30, Grunewald, near Berlin 5 Germany, have invented certain new and useful Improvements in Mercury Switches for Railways and the Like, of which the following is a specification.

The present invention relates to railway- 10 signal operating devices and has for its object improvements in mercury switches for use with the same.

In means which enable a traveling train to act on fixed working devices, accidental 15 action on the devices as well as a breakdown of the intended operation must be prevented as much as possible.

Known means in which mercury switches operated by a vehicle passing along a rail are 20 employed alone or in combination with insulated rails fulfill these conditions to a certain extent. Nevertheless when the level of the mercury is not at the correct height it may happen that either a detent or lock is 25 prematurely released, or a detent and signal are not released at all.

Now an important object of the present invention is to obtain a higher degree of certainty of working by arranging a second 30 place where the circuit is closed in a mercury switch which is operated by a bending rail, by means of which second contact the position of the mercury in the switch can be controlled. This control can be effected by 35 means of audible or visible signals, the release of which is dependent on the second contact and indicates that the level of the mercury has passed the limits when the intended action of the mercury switch no 40 longer takes place. If this control merely consists in a signal, such as a colored disk or a bell, which is perceptible, visible or audible to the pointsman or signal-man, it still remains left to the conscientiousness of the pointsman 45 to rectify at the right time the defect which is indicated by the signal. If the controlling current is used however for making conditions of working which are necessary for the unimpeded passage of the train, the points- 50 man or signal-man is compelled to report the indication at once. In this manner a higher degree of safety is obtained. Such conditions of working are made for example by placing a signal in various positions.

55 In order that the invention may be clearly

understood, reference is made to the accompanying drawing in which two embodiments are represented diagrammatically by way of example, and in which:

Figure 1 shows a device which comes into 60 operation behind the last axle of the train, whereas Fig. 2 represents a device which comes into action under the first axle, and Figs. 3 and 4 show part of the means in Fig. 2 in modified positions.

65 In both examples represented in the drawing the train is to set the signal (13) automatically at "stop", and is to make its release thereafter into the "line clear" position dependent on a block apparatus being 70 worked.

75 Referring to Fig. 1 in the drawing, 1 denotes the locking rod of a block apparatus, 2 a contact controlled by it, and 3, 4, 5 a press-button lock which is influenced by a spring 6, armature 7 and electromagnet 8; by depressing the rod 1 the contact-lever 5 is brought into the position in which it is shown in the drawing, in which it keeps the switch-arm 9 closed and the catch 4 in the locked 80 position.

85 14 is the winding of an electric signal-wing coupling of known kind for the signal-wing 13. The relay consisting of the parts 15 to 18 makes the block-apparatus and the signal dependent on the passage of the train in a manner which is known in itself, but which is described again hereafter.

90 The mercury switching device has a receptacle or switch-box 21 attached to the rail 20, and besides the current-supply device 22 which dips into the cup 23 and pipe 24 there is a second current-supply device 26 in addition, the point of which is continuously below the normal surface 27 of the 95 mercury. 25 and 28 are small outlets, 29 is the pressure chamber, 30 the diaphragm and 31 the plunger of the known mercury switch operated by a bending rail.

100 When the rail 20 is traveled over by a vehicle and mercury is forced by the diaphragm through pipe 24 into cup 23, the following circuit is closed:—battery 10, conductor 11, arm 9, winding 15, conductor 35, current-supply device 22, mercury in pressure chamber 29, conductor or earth 32, terminal 12, and back to battery 10; the armature 16, which is attracted by the magnet 15 of the relay, connects the two magnet windings 15 and 8 on one side to the insulated rail 19 by 110

means of the contacts 17 and 18, whereby, on account of the following circuit, *i. e.*:—battery 10, conductor 11, arm 9, magnet winding 15, contact 18, conductor 36, insulated rail 19, through the axle of the train to rail 20, conductor 32, terminal 12, battery 10,—the relay-magnet 15 remains operative independent of the state of the mercury switch, and whereby, after the last axle of 10 the train has passed, the magnet 8 is also energized and the press-button lock released by the following circuit, *i. e.*:—battery 10, conductor 11, arm 9, magnet winding 15, contact 18, conductor 36, insulated rail 19, 15 conductor 37, contact 17, magnet winding 8, terminal 12 and battery 10,—the contact-lever 5 which is released by the armature-lever 7 being snapped upwards by the spring 6. The hitherto closed signal-coupling circuit, *i. e.*:—battery 10, conductor 11, arm 9, arm 2, conductor 33, magnet winding 14, conductor 34, current-supplying device 26, mercury 29, conductor 32, terminal 12, and battery 10—is thereby also broken at the 20 contact 9 and the signal-wing 13 goes back automatically into its normal or “stop” 25 position.

On account of the connection of the signal-coupling 14 through the conductor 34 with the second device 26 for closing the circuit of the mercury switch, the quantity of mercury which is present and the height of the same is controlled which is of great importance for the safety of working the line. If, 30 for example, the coupling were connected, as is usual, simply directly to earth, at its battery-terminal 12 for example, and if there was an insufficient quantity of mercury in the switch-box 29, when the train passed over this section of the line the contact 22, 29 would not be closed and thus the signal could not be set to “stop.” In the above described arrangement in accordance with the present invention on the contrary, the signal 35 could not be placed at “line clear” in the case of a deficiency of mercury, as the above described signal-coupling circuit would be interrupted at the control contact 26.

As is represented in Figs. 2 to 4, the same 40 control can also be obtained in a device which returns the signal into its normal position under the action of the first axle.

With the exception of the insulated rail and the relay, Fig. 2 contains all the principal parts shown in Fig. 1. The second contact-pin 26 dips into a pipe 39 connecting with the pipe 24 and chamber 29, which arrangement is different from that in Fig. 1.

When a train travels past the part of the 45 rails where this mercury switch is situated, as indicated in Fig. 3, a considerable quantity of mercury is forced by the first wheel 41 from the receptacle 29 through the pipes 24 and 39 into the upper chamber 40, where- 50 by the contact 22 is closed, whereas the con-

tact 26 remains closed. The following circuit in Fig. 2, *i. e.*:—battery 10, conductor 11, arm 9, magnet winding 8, conductor 38, current-supply device 22, mercury 29, rail 20, conductor 32, battery terminal 12 and 55 battery 10,—causes the release of the press-button lock and the signal to be placed at “stop” by interrupting at contact 9 the signal-coupling circuit, *i. e.*:—battery 10, conductor 11, arm 9, arm 2, conductor 33, 70 magnet winding 14, conductor 34, contact-pin 26, mercury 29, rail 20, conductor 32, battery terminal 12, and battery 10.

As soon as the first wheel leaves the rail over the mercury switch, the level of the 80 mercury in the receptacle 29 at once sinks so low that the contact 26 is also interrupted (Fig. 4), as the mercury which is in the chamber 40 can flow back only slowly through the small opening 28 into the receptacle 29. In this manner the signal-coupling circuit is broken at a second place so that the signal is returned to the “stop” 85 position even in case the press-button releasing device breaks down. Moreover, in 90 this form the position of the level of the mercury is controlled in the normal position (Fig. 2) by the signal-coupling circuit.

The electrical arrangement of the press-button locking magnet protects, generally 95 speaking, from the danger of the mercury being too high in the receptacle of the mercury switch, and this magnet in this case prevents the signal being set at “line clear.”

An electromagnet can be used to prevent 100 premature release on account of the level of the mercury being too high, which magnet releases the signal-lever only when it is without current, it being temporarily inserted between the current-supplying pin 22 or a 105 third similarly arranged contact and the pole 11 of the battery. The same purpose can be served by an interrupter in the circuit of the relay-magnet or of the press-button locking device, which interrupter 110 can only be closed after the level of the mercury has been controlled.

What I claim as my invention and desire to secure by Letters Patent is:—

1. A mercury switch, for operation by a 115 vehicle passing along a railway, comprising a receptacle containing mercury, a diaphragm in the receptacle contacting the mercury, a rail-actuated plunger for moving said diaphragm, and a circuit-closing device in said 120 receptacle adapted to be contacted by the mercury, in combination with a second circuit-closing device in said receptacle normally contacting the mercury, for the purpose of controlling the level of the mercury in 125 said receptacle.

2. A mercury switch, for operation by a vehicle passing along a railway, comprising a receptacle containing mercury, a diaphragm in the receptacle containing the mercury, a 130

- 5 rail-actuated plunger for moving said diaphragm, and a contact in said receptacle adapted to be contacted by the mercury, in combination with a second contact in said receptacle normally contacting the mercury, and electric means for controlling a signal 40 electrically connected with said second contact and the mercury, the arrangement being such that the circuit through the second contact must be closed in order to make conditions of working necessary for the unimpeded 45 passage of a vehicle.
- 10 3. A mercury switch, for operation by a vehicle passing along a railway, comprising a receptacle containing mercury, a diaphragm in the receptacle containing the mercury, a rail-actuated plunger for moving said diaphragm, and a contact in said receptacle adapted to be contacted by the mercury, in 50 combination with a second contact in said receptacle normally contacting the mercury, a signal coupling, electric block-apparatus mechanism, and a battery for operating the signal coupling in series with one another and 55 electrically connected with said plunger, whereby a current cannot be sent through said signal coupling to operate the signal unless the second contact contacts the mercury in the receptacle.
- 15 30 4. A mercury switch, for operation by a vehicle passing along a railway, comprising a switch-box containing mercury, partitions in said box dividing the same into compartments communicating with one another and 60 one above the other, a diaphragm closing one end of the lowest compartment, a rail-actuated plunger on said diaphragm and a contact in the highest compartment normally above the mercury, in combination with a second contact in a compartment normally 65 contacting the mercury, whereby when said plunger is temporarily depressed mercury is temporarily sent into contact with the former contact and then flows away from the second contact, as set forth.
- 20 5. A mercury switch, for operation by a vehicle passing along a railway, comprising a receptacle containing mercury, a pipe carrying a cup connecting with the bottom of the receptacle, said cup having a small hole in the same, a diaphragm closing one end of the receptacle, a rail-actuated plunger on said diaphragm and a contact in said cup normally above the mercury, in combination with a second pipe communicating with the bottom of the former pipe and a second contact in the latter pipe normally contacting the mercury, the arrangement being such 70 that when the plunger is temporarily depressed the mercury is forced into said cup and temporarily contacts the contact therein, whereas the contact of the second contact with the mercury is then temporarily broken, as set forth.
- 25 35 In testimony whereof I have signed my name to this specification in the presence of two witnesses.

ROBERT PFEIL.
